UNITED STATES PATENT OFFICE.

HENRY SHAPIRO, OF PHILADELPHIA, PENNSYLVANIA.

BRUSH.

Application filed September 6, 1923. Serial No. 661,126.

To all whom it may concern:

Be it known that I, HENRY SHAPIRO, a citizen of the United States, residing at Philadelphia, in the county of Philadelphia and State of Pennsylvania, have invented certain new and useful Improvements in Brushes, of which the following is a specification.

My invention relates to brushes, more particularly to tooth brushes of the type in which the paste is fed to the bristles from the handle. The object is to provide a tooth brush of simple construction having paste feeding means which will not clog the bristles with paste, and to provide a brush handle which will readily receive a new supply of paste from an ordinary tube or be wholly removable as a paste cartridge.

These objects, and other advantageous ends which will be described hereinafter, I attain in the following manner, reference being had to the accompanying drawings in which

Figure 1 is an inverted plan view of a brush constructed in accordance with my invention,

Figure 2 a central section through the brush shown in Figure 1,

Figure 3 a section on line 3—3 of Figure 2, illustrating the trap door in an open position,

Figure 4 a view similar to Figure 3 showing the trap door in a closed position,

Figure 5 an enlarged fragmentary section similar to that shown in Figure 2,

Figure 6 a view similar to Figure 5 showing the parts moved into another position,

Figure 7 a section on line 7—7 of Figure 5, and

Figure 8 a section on line 8—8 of Figure 6.

Referring to the drawings 1 indicates a bristle head having bristles 2 mounted at one end and a tubular feed screw 3 screwed into the other end. The feed screw is provided with a bearing part 4, a flange 5, a threaded part 6, a counter-bore 7, and an opening 8. A collar 9 is rotatably mounted on the bearing 4 between the flange 5 and the end of the head and is provided with a knurled part 10 and a threaded part 11 for receiving one end 12 of a tubular or hollow handle 13 which has pressed therein longitudinal ribs 14. The other end 15 of the handle is threaded to receive a knurled cap 16 having a recess 17 for receiving the end

of the feed screw and an opening 18 to serve as a passage for air to and from the housing. A threaded piston 19 travels on the threaded part 6 of the feed screw and is provided with notches 20 in its circumference for receiving the longitudinal ribs 14 on the handle. This disposition of the piston, relatively to the handle and the feed screw, slidably keys it to the handle but holds it in threaded engagement with the feed screw. Thus by turning the handle, the piston will travel on the threaded part of the feed screw and force the paste out of the handle. A delivery tube 21 is slidable within the bristle head and the feed screw and has one end provided with a needle point 22 and an outlet 23 and the other end provided with an enlarged part 24, slidable within counter-bore 7, and an inlet 25. The inlet is adapted to communicate with the opening 8 in the feed screw when the delivery tube is pulled into its extended position, as shown in Figures 1 and 2, so that paste may be fed onto the bristles. To pull the delivery tube into this position or push it back into the bristle head, I provide a lug 26 secured to the delivery tube and adapted to travel within a slot 27 in the bristle head.

To prevent dust or other material from accumulating on needle point 22, when the tube is in its closed position, I provide a trap door 28 of any suitable construction to close the opening as shown in Figures 3 and 4.

To use the brush, delivery tube 21 is pulled out of the bristle head until the enlarged part 24 abuts the end of counter-bore 7. The handle 13 is then rotated to force paste out of opening 23, and said tube 21 is slid back into the bristle head. During this movement the paste around outlet 23 will be scraped from the needle point by the bristles as it passes therethrough and the inlet 25 will leave opening 8 in the feed screw and cut off communication therewith. After the delivery tube has entered the bristle head, the trap door 28 will close behind the needle point and the brush is then ready for use.

During the sliding movement of the delivery tube within the feed screw, the air displaced within the feed screw by the delivery tube is permitted to pass out through opening 18 in the cap.

To replenish the paste supply with an ordinary tube, cap 16 is removed from the

handle and the handle turned, opposite to the feeding direction, until the piston comes out of the handle. The handle is then filled with paste from an ordinary tube and the piston and cap replaced. To replenish the paste supply by the cartridge, the handle is unscrewed from the collar 9 and the piston from the threaded part of the feed screw. The cartridge which is similar to the handle 10 is then screwed onto the collar. The other end of the cartridge, which is provided with a cap similar to cap 16, is removed and the piston screwed onto the feed screw. The cap is then replaced and the cartridge is 15 ready for use.

A brush constructed as above described will not clog the bristles with paste, is simple in construction, and cheap to manufacture.

While I have described my invention as 20 taking a particular form, it will be understood that the various parts may be changed without departing from the spirit thereof, and hence I do not limit myself to the precise construction set forth, but consider that 25 I am at liberty to make such changes and alterations as fairly come within the scope of the appended claims.

Having thus described my invention, what 30 I claim as new and desire to secure by Letters Patent is:—

1. A brush including a bristle head; a hollow handle rotatably connected thereto; a delivery tube movable in the head and adapted to communicate with the interior 35 of the handle when moved to open position and cut off communication therewith when moved to closed position; and means within said handle and actuated by rotation of said handle for feeding material through the delivery tube.

2. A brush including a bristle head; a hollow handle rotatably connected thereto; a tubular feed screw having one end mounted stationary in the head and the free end 45 projecting within the handle and having an opening in its side; a delivery tube slid- able within the head and the feed screw and adapted to communicate with the opening when slid to open position and cut off 50 communication therewith when slid to closed position; and means movable on said feed screw by rotation of said handle for feeding material through the delivery tube.

3. A brush including a bristle head; a hollow handle rotatably connected thereto; a tubular feed screw having one end mounted on the head and the free end projecting within the handle and having an opening in 55 its side; a delivery tube slidable within the head and the feed screw and adapted to communicate with the opening when slid to open position and cut off communication therewith when slid to closed position; and a threaded piston adapted to travel on the feed screw, and slidably keyed to the handle,

for feeding material through the delivery tube.

4. A brush including a bristle head; a hollow handle rotatably connected thereto; a tubular feed screw connected to the head and extending within the handle and having a counter-bore and an opening in its side; a delivery tube slidable within the head and having an enlarged part slidable within the counter-bore, the delivery tube being adapted to communicate with the opening when slid to open position and cut off communication therewith when slid to closed position; and means for feeding material through the delivery tube.

5. A brush including a bristle head; a tubular feed screw mounted stationary on said bristle head and having a side opening and a cylindrical bearing portion; a hollow handle mounted on said head with means 85 rotatably engaging said bearing portion; a delivery tube within the head and feed screw and adapted to communicate with said opening; and means on said feed screw actuated by rotation of said handle for 90 forcing material from the handle through the delivery tube.

6. A brush including a bristle head; a tubular feed screw mounted stationary thereon and having a side opening and a 95 cylindrical bearing portion; a collar rotatably mounted on said portion; a hollow handle removably secured to the collar; a delivery tube within the head and feed screw and adapted to communicate with said 100 opening; and means on said feed screw actuated by rotation of said handle for forcing material from the handle through the delivery tube.

7. A brush including a bristle head; a 105 tubular feed screw mounted stationary on said head and having an opening in its side and a bearing portion; a hollow handle rotatably mounted with means at one end on said bearing portion; a cap secured to the 110 other end of said handle and having an air vent communicating with the interior of the feed screw; a delivery tube slidable within said head and said feed screw and adapted to communicate with said opening when slid 115 to open position and cut off communication therewith when slid to closed position; and means within the handle which is actuated by rotation of said handle for feeding material through the delivery tube.

8. A brush including a bristle head; a tubular feed screw mounted stationary thereon and provided with a side opening and a bearing portion and a flange; a collar rotatable on said bearing portion between 125 said flange and said bristle head; a hollow handle having one end detachably secured to said collar; a delivery tube within the feed screw and adapted to communicate with said opening when in open position and 130

- cut off communication therewith when in mounted on said bearing portion; a hollow closed position; and means movable on said feed screw by rotation of said handle for feeding material through the delivery tube.
- 5 9. A brush including a bristle head; a hollow handle rotatably mounted thereon; a tubular feed screw mounted on the head and projecting within the handle and having an opening; a delivery tube slidable in said head and said feed screw and having a pointed head with an outlet movable into said bristles and having a side opening near the other end, the opening in the delivery tube being adapted to communicate with the 10 opening in the feed screw when the delivery tube is slid to open position and cut off communication therewith when slid to closed position; and means for forcing material through the delivery tube.
- 15 10. A brush including a bristle head; a tubular feed screw mounted stationary thereon and provided with a bearing portion and a side opening; a collar rotatably

25 to said collar; a handle having one end removably secured to said collar; a cap removably attached to the other end of said handle and having an air vent communicating with the interior of the feed screw; a delivery tube slidable within the feed screw and having a side 30 opening adapted to communicate with said opening when slid to open position and cut off communication therewith when slid to closed position, and a piston slidably keyed to said handle and threaded to engage and 35 move along said feed screw by rotation of said handle for forcing material through the delivery tube.

35 In testimony whereof I have signed my name to this specification in the presence of 40 two subscribing witnesses.

HENRY SHAPIRO.
